CYCLAMMONIUM QUATERNARY SALTS AND
DYES PRODUCED THEREOF

Paul Daniel Dreyfuss, Van Nuys, and Bela Gaspar,
Beverly Hills, Calif.; said Dreyfuss assignor to
said Gaspar

No Drawing. Application May 17, 1949,
Serial No. 93,818

3 Claims. (Cl. 260—240.4)

1

This invention relates to cyclammonium quaternary salts, to a process for preparing them, and to dyes made therefrom.

A class of intermediates of great value for the preparation of polymethine dyes consists of the cyclammonium alkyl quaternary salts having the following structure

where A stands for a methyl or a substituted methyl group; R stands for an alkyl group; X stands for an anion, and Y stands for a chain of from two to three carbon atoms.

Some of these cyclammonium alkyl quaternary salts are available by condensing the bases

with alkyl halides or alkyl toluenesulfonates, RX. The condensation of these bases with the corresponding aryl derivatives, however, is not possible; i. e., the cyclammonium salts of the above indicated structure where R stands for an aryl residue, cannot be obtained by the usual methods.

In the co-pending applications entitled "N-Arylthiazolinium Quaternary Salts" and "Penthiazolinium Quaternary Salts," filed on an even date herewith, it is disclosed that thiazolinium and penthiazolinium quaternary salts can be obtained by condensing thioamides A—CS—NHR with compounds X—Y—X, where A and Y have the above explained meaning, where R stands for an alkyl or an aryl residue and where X stands for a residue which is able to accept an electron to form an anion, such as a halogen atom or an alkylsulfo or arylsulfo residue. The residue X which functions as an anion in the quaternary salt and as a homeopolar substituent in the starting material from which quaternary salt is obtained, is called "anionide substituent" in the appended claims.

We have now found a new method for preparing cyclammonium quaternary salts of the above type where R stands for alkyl or aryl. By means

of our new method many quaternary salts, heretofore unknown, are made available for the first time.

In accordance with our invention, we prepare the cyclammonium quaternary salts by condensing one mol of a compound R—NH—Y—X with one mol of a compound A—CS—NB₂, where Y, X and A have the explained meaning; where R stands for alkyl or aryl, and where B stands for hydrogen or its equivalents. The condensation is performed preferably in the presence of one mol of an acid, HX, which serves to stabilize the compound R—NH—Y—X which otherwise tends to condense with itself, and to bind the base NB₂ liberated in the condensation. The condensation follows the following scheme:

Most of these condensations are exothermic, starting at temperatures below 200° and giving excellent yields. The starting materials are easily available; the condensations are easily performed; the reaction is highly versatile, rendering accessible substituted thiazolinium and penthiazolinium salts which cannot be obtained by any other method. These features make our invention a valuable instrument in obtaining cyclammonium quaternary salts and dyes derived thereof.

The formation of a cyclammonium R quaternary salt from the components R—NH—Y—X and A—CS—NB₂ is unexpected. Gabriel and co-workers [Berichte 27, 3519 (1894); ibid. 29, 2610 (1896)] prepared bases

from NH₂—Y—X and A—CS—NH₂. It seemed probable that the ammonia liberated in Gabriel's reaction was furnished from the component

$\text{NH}_2-\text{Y}-\text{X}$ while the thiazoline nitrogen was furnished from the thioamide. This mechanism seemed probable particularly in view of Todd et al. [Berichte 69, 217 (1936)] who found that from thioamides, $\text{A}-\text{CS}-\text{NHB}$, cyclammonium B quaternary salts can be obtained.

According to our invention, however, the residue B in the thioamide influences the ease but not the course of the reaction, i. e. the same cyclammonium R quaternary salt is obtained whether thioacetyl amide, methylamide, xylidide, bromanilide or naphthalide are condensed with compounds $\text{R}-\text{NH}-\text{Y}-\text{X}$.

Suitable compounds $\text{A}-\text{CS}-\text{NB}_2$ in the synthesis according to this invention are e. g. the following:

Thioacetamide
Thioacetanilide
Thiopropionamide
Thiobutyramide
 β -Methoxy thiopropionamide
 α -Phenyl thioacetamide
 α -Methoxy thioacetamide
 α -Phenoxythioacetamide
 α -Ethylthioglycolic acid thioamide

Other thioamides such as thioformamide, thio-benzamide or thioterephthalamide (which can be reacted with compounds $\text{R}-\text{NH}-\text{Y}-\text{X}$ in proportions 1:1 or 1:2) are equally suitable in the preparation of cyclammonium R quaternary salts.

The compounds $\text{R}-\text{NH}-\text{Y}-\text{X}$ used in our invention are preferably obtained from the corresponding alcohols $\text{R}-\text{NH}-\text{Y}-\text{OH}$ and isolated as salts $\text{R}-\text{NH}-\text{Y}-\text{X}$, HX , e. g., the alcohols can be converted into the bromo compounds, according to the method described by Pearlman, Journal of the American Chemical Society, vol. 70, page 871 (1948), or into the sulfuric acid esters such as described by Emde, Helvetica Chimica Acta, vol. 12, page 402 (1929). Other methods of conversion of alcoholic groups (OH) into anionide groups (X) are well known in the art.

Typical of suitable compounds $\text{R}-\text{NH}-\text{Y}-\text{OH}$ are:

β -Methylaminoethanol
 β -Isoamylaminoethanol
 β -Allylaminoethanol
 β -Cyclohexylaminoethanol
 β -Anilinoethanol
 β -p-Toluidinoethanol
 β -o-Chloranilinoethanol
 β -p-Ethoxyanilinoethanol
 β -(1-naphthylamino) ethanol
 β -(2-naphthylamino) ethanol
2-(β -hydroxyethylamino) diphenylene oxide
 β -n-Propylamino-n-propanol
 β -Anilino-n-butanol
 β -Ethylamino-isopropylalcohol
(β -Hydroxy- γ -phenoxypropyl)-aniline
Ephedrine
Conhydrine
Pseudoconhydrine
2-methylaminocyclohexanol
3-methylaminoborneol
1,2,3,4-tetrahydro-3-hydroxy-benzo[h]quinoline
1,2,3,4-tetrahydro-2-hydroxy-benzo[f]quinoline
N,N'-di-(β -hydroxyethyl)-p-phenylenediamine
 α -Phenyl- β -anilinoethanol
 α , β -Diphenyl- β -p-chloroanilinoethanol
Methyl- α -pyrrolidylcarbinol
 γ -Ethylaminopropanol
 γ -Cyclohexylaminopropanol

γ -Anilinopropanol
 γ -o-Chloranilinopropanol
 γ -p-Ethoxyanilino-n-butanol
 γ -(1-naphthylamino) propanol
5 γ -Methylamino-n-butanol
4-hydroxypiperidine
2-(β -hydroxyethyl) piperidine
(2-hydroxy-hexahydrobenzyl) aniline
Nortropine

10 In addition to the compounds $\text{R}-\text{NH}-\text{Y}-\text{X}$ which are obtained from the alcohols of the foregoing list, there are a few which are obtained from other starting materials; such compounds are, e. g.: γ -chloro- β -hydroxypropylaniline, and o-(methylamino) benzylbromide.

By combination of thioamides $\text{R}-\text{CS}-\text{NB}_2$ with compounds $\text{R}-\text{NH}-\text{Y}-\text{X}$ a most diversified group of cyclammonium R quaternary salts is available. The carbon chain, represented by Y, is in most cases saturated. Of particular interest are those compounds in which said carbon chain Y is substituted. The substituents are primarily hydroxyl groups, aliphatic or aromatic groups, but other substituents such as nitrile, sulfone, sulfonamide groups which do not interfere with the cyclammonium salt formation are within the scope of the present invention. Members of the chain Y can furthermore be part of rings. For example, by melting thioacetamide with 4-iodopiperidine hydroiodide, a compound is obtained which is believed to have the following constitution

35 and from N-methylhexahydro-o-chloroaniline another type of bicyclic compound is obtained, i. e., a hexahydrobenzthiazolium quaternary salt.

40 45 The following examples will serve to illustrate further the manner of obtaining cyclammonium quaternary salts and of preparing dyes thereof.

EXAMPLE 1

2-methyl-3-ethyl thiazolinium perchlorate

Formula I

($W=-$; $X=H$; $Y=C_2H_5$; $Z=ClO_4$)

55 Twenty-three grams of β -bromo-diethylamine hydrobromide and 7.5 grams of thioacetamide were mixed and heated in a boiling waterbath for 20 minutes. The mass melted but thickened again after a short time. The mass was dissolved in 30 ml. of water, and a solution of 20 gr. of sodium perchlorate in 20 ml. of water was added. 60 The quaternary thiazolinium perchlorate separated in crystalline form. It was filtered and washed with isopropylalcohol. By recrystallization from isopropylalcohol the perchlorate was obtained as colorless crystals, melting at 180-81° C. The yield was 17.2 grams (75% of theory).

5

EXAMPLE 2

2-methyl-3-ethyl thiazolinium iodide

(Formula I: $W=--$; $X=H$; $Y=C_2H_5$; $Z=I$)

Twenty-three grams of β -bromoethylamine hydrobromide and 7.5 grams of thioacetamide were melted as in the foregoing example. The mass was slurried in isopropylalcohol and filtered. The residue was ammonium bromide. The filtrate was warmed, a warm solution of 15 grams of sodium iodide in isopropylalcohol was added, and the precipitated sodium bromide was filtered off. The filtrate (200 ml.) was cooled whereby the quaternary iodide crystallized. The raw iodide was highly hygroscopic. It was suspended in boiling acetone to which methanol was added dropwise until the crystals dissolved completely. The pure iodide crystallized by cooling. It was identical in every respect with the salt prepared according to Brooker, *Journal of American Chemical Society*, vol. 58, page 664 (1936).

EXAMPLE 3

2-methyl-3-phenylthiazolinium iodide

(Formula: $W=--$; $X=H$; $Y=C_6H_5$; $Z=I$)

Twenty-eight grams of N - β -bromoethylaniline hydrobromide, 7.5 grams of thioacetamide and 30 ml. of chlorobenzene were stirred and heated in an oil bath for one hour, starting at 95° C. and raising the temperature up to 110° C. While heated, the mass first dissolved and shortly afterwards solidified again. After cooling, the mass was filtered, washed with 40 ml. of commercial ether and digested in 100 ml. of boiling isopropylalcohol. Without separating the solid ammonium bromide, 15 grams of sodium iodide were added, the mixture of ammonium and sodium bromides were removed by filtration through a heated Büchner filter, and the residue was extracted with 50 ml. of hot isopropylalcohol. The combined filtrates were cooled whereby the quaternary iodide crystallized. The crystals were filtered off, and the filtrate served for a further extraction of the above inorganic residue whereby a second crop of quaternary iodide was obtained. The iodide, recrystallized from isopropylalcohol, formed colorless crystals melting at 181-182° C. The yield was 25.7 grams (84% of theory).

If smaller batches than that above are run, the mixture of the components may be melted without a solvent. However, if the temperature is not carefully watched, the reaction gets out of control and the raw product then will contain appreciable amounts of a yellow dye, decreasing the yield. The reaction is much smoother in the presence of a solvent such as chlorobenzene. The reaction was successfully run in isopropanol, and even in water and in diluted aqueous hydrochloric acid the quaternary salt formed, but the yield was considerably smaller.

If the thioacetamide is replaced with an equivalent amount of thioacetanilide, the same quaternary salt and, as byproduct, aniline hydrobromide is formed. However, if thioacetanilide is melted with bromoethylamine hydrobromide, no quaternary salt forms; only aniline hydrobromide and 2-methylthiazoline can be isolated from the reaction mixture.

If thioacetamide is melted with free bromoethylaniline, ammonia gas escapes, and a residue is obtained which consists partly of diphenyl-

5

6

piperazine and partly of quaternary salt from which the iodide, melting at 181-182° C. can be obtained in only inferior yield.

EXAMPLE 4

2-methyl-3-phenylthiazolinium bromide

(Formula I: $W=--$; $X=H$; $Y=C_6H_5$; $Z=Br$)

An intimate mixture of 28 grams of N - β -bromoethylaniline hydrobromide and 7.5 grams of thioacetamide was heated to 100° C. When the reaction started to become violent it was moderated by cooling, and after the reaction subsided, the mass was heated to 100° C. for one hour. The mass was extracted with isopropanol, and from the extract the quaternary bromide crystallized. It was recrystallized from isopropylalcohol, forming colorless crystals, melting at 204° C.

20

EXAMPLE 5

2-methyl-3-phenylthiazolinium perchlorate

(Formula I: $W=--$; $X=H$; $Y=C_6H_5$; $Z=ClO_4$)

25

The melted mass, obtained as in the foregoing example, was dissolved in water and precipitated with sodium perchlorate. The product, recrystallized from ethanol, formed colorless crystals, melting at 160° C.

EXAMPLE 6

2-methyl-3-phenylpentathiazolinium perchlorate

(Formula I: $W=CH_2$; $X=H$; $Y=C_6H_5$; $Z=ClO_4$)

30

Fifteen grams of N - γ -bromopropylaniline hydrobromide and 3.8 grams of thioacetamide were melted for 15 minutes in a boiling water bath. The mass was dissolved in water and precipitated with sodium perchlorate. 8.0 grams of pure perchlorate, melting at 129° C. were obtained.

35

γ -Hydroxypropylaniline, serving as starting material for the bromopropylaniline of this example, could be obtained in good yield by heating trimethylene chlorohydrin with a 100% excess of aniline in water in the presence of traces of potassium iodide.

40

EXAMPLE 7

By condensing N - γ -bromopropyl-ethylamine hydrobromide with thioacetamide and proceeding as in Example 3, a pentathiazolinium iodide (Formula I: $W=CH_2$; $X=H$; $Y=C_2H_5$; $Z=I$) was isolated which was identical with the 2-methylhydro-1:3-thiazine ethiodide, described by Hamer and Rathbone, *Journal of the Chemical Society*, 1943, page 247.

45

The melting points of other quaternary salts, prepared by the same method, are reported in the following table:

(Formula I: $Z=ClO_4$)

	W	X	Y	M. P.
1	$-CH_2-$	H	$p-C_6H_5-C_6H_4-$	231°.
2		CH_3-	C_6H_5-	172°.
3		C_2H_5-	cyclohexyl-	oil.
4		CH_3-	$p-CH_3-C_6H_4-$	108-109°.
5		$HO-$	$p-CH_3-C_6H_4-$	oil.
6		H-	α -Naphthyl-	173°.
7		H-	$p-C_6H_5-C_6H_4-$	212-214°.

¹ The α -phenyl- β -(cyclohexylamino) ethanol, M. P. 89° C., obtained from cyclohexylamine and phenylethylene oxide, easily decomposes if boiled with aqueous hydrobromic acid. However, it can be converted into N -(β -bromo- β -phenylethyl) cyclohexylamine hydrobromide, serving as starting material in the preparation of quaternary salt #3, by heating with aqueous hydrobromic acid (48%) for only 15 minutes at waterbath temperature.

Those cyclammonium quaternary salts of this invention which have attached in the 2-position a sidechain $-\text{CH}_2-\text{R}'$ where R' stands for hydrogen or its equivalents, can be condensed with ortho formates in the presence of acid binding agents, e. g., in pyridine, or with sodium formate in acetic anhydride to give symmetrical carbocyanine dyes. By replacing the orthoformate with other orthoesters, meso substituted symmetrical carbocyanines are obtained which can be prepared as well by other methods known in the art. The following examples will serve to illustrate further the manner of obtaining such dyes.

EXAMPLE 8

3,3'-diphenylpentiazolino carbocyanine perchlorate

Two and nine-tenths (2.9) grams of 2-methyl-3-phenylpenthiazolinium perchlorate and 2.2 grams of ethyl orthoformate in 10 ml. of anhydrous pyridine were refluxed for one hour. The dye was precipitated with ether and recrystallized from methanol. It was a brown powder which, after previous shrinkage, melted at about 210° C. The methanol solution of the dye had an absorption maximum at about 483 m μ while the absorption maximum of a pyridine solution was at about 490 m μ . The sensitivity range of a silver chlorobromide emulsion containing 20 mg. of the dye per liter emulsion extended to about 540 m μ with a maximum at about 510 m μ .

EXAMPLE 9

Other symmetrical carbocyanine dyes are listed in the following table:

infra-red range, are prepared from 2 mols of quaternary salt and 1 mol of glutacondialdehyde in cold pyridine with triethylamine. The absorption maxima of some of these dyes are reported in the following table:

Formula II: X=H, Y=C ₆ H ₅ , Z=ClO ₄		Absorption maximum of methanol solution, mu
n	W	
2	CH ₂	565
2	CH ₂	585
3	CH ₂	670
3	CH ₂	700

EXAMPLE 11

20 Unsymmetrical carbocyanines derived from the quaternary salts of this invention are represented by the dye

30 which forms reddish brown crystals melting at 268° C. The methylalcoholic solution absorbs with a maximum at about 541 mu. A silver-bromide emulsion is sensitized in the long-wave green range of the spectrum.

35 These unsymmetrical carbocyanines can be obtained e. g., by condensing the quaternary salts of this invention with equimolecular proportions of other quaternary salts in the presence of ortho esters or acid anhydrides. They can be obtained furthermore by condensing 2-methyl quaternary salts with 2-arylamino vinyl quaternary salts. A method for obtaining meso methyl substituted unsymmetrical cyanine dyes consists e. g., in condensing the quaternary salts of our invention, or derivatives thereof, with reactive compounds such as methylene bases, in suitable solvents whereby

Formula II: $n=1$				Appearance	M. P.	Absorption maximum of methanol solution, mu
W	X	Y	Z			
-----	H	C ₂ H ₅ -----	I	Brown crystals with metallic luster.	255°-----	455
-----	H	C ₆ H ₅ -----	I	Brown crystals with bronze luster.	253°-----	465
-----	C ₆ H ₅ -----	cyclohexyl-----	ClO ₄	Orange needles-----	164-166°-----	458
-----	H	C ₂ H ₅ -----	I	Red crystals-----	243°-----	465
-----	CH ₃	C ₆ H ₅ -----	ClO ₄	Brown powder-----	Decomp-----	470

All of these dyes sensitize chlorobromide emulsions with maxima in the range between 475 and 500 μ , the penthiazolino carbocyanines ($W=CH_2$) imparting a sensitizing maximum at a longer wave length than the thiiazolino carbocyanines ($W=-$), and the N-aryl carbocyanines ($Y=aryl$) at a longer wave length than the N-alkyl carbocyanines ($Y=alkyl$).

EXAMPLE 10

If 2 mol equivalents of quaternary salt and 1 mol equivalent of propenedianilide are condensed in pyridine with trimethylamine, dicarbocyanine dyes form which are strong red sensitizers. The analogous tricarbocyanines which sensitize in the

60 part of the cyclammonium derivatives decompose furnishing the acid derivatives necessary for the formation of the polymethine chain. For example, the dithio acid which is obtained from 2-methyl-3-phenylthiazolinium iodide, carbon 65 disulfide and triethylamine in methanol and which melts, depending on the rate of heating, between 125 and 155° C. is a suitable starting material for meso mercapto dyes (upon addition of alkyl halides) and for meso methyl dyes. Said 70 dithio acid, if refluxed with methylbenzthiazole ethiodide in ethanol for thirty minutes, is converted into the carbocyanine of the above formula

Analogous dyes are obtained by heating 2-75 methyl-3-phenylthiazolinium iodide with 1-

acetyl methyl-2-ethylbenzosenazoline in propionic anhydride, by condensing 3- β -naphthylthiazoline-2-methine- ω -aldehyde with 1-ethyl-2-methyl-3-phenylbenzimidazolium ethyl sulfate or by condensing the 2-(2-acetanilidovinyl)-3-phenylpenthiazolinium perchlorate, disclosed below, with methylbenzoxazolium ethyl iodide.

The quaternary salts of our invention, which have attached in the 2-position a sidechain $-\text{CH}_2-\text{R}'$ where R' stands for hydrogen or its equivalents, can be condensed with diarylformamidines to give β -arylamino vinyl derivatives thereof. They can also be condensed with diarylformamidines in the presence of acid anhydrides such as acetic anhydride, propionic anhydride and butyric anhydride to give β -acylarylamino vinyl derivatives thereof. These β -acylarylamino vinyl-cyclammonium quaternary salts can be obtained as well by first fusing the 2-methyl-cyclammonium quaternary salts with a diarylformamide, followed by acylation with an acid anhydride.

EXAMPLE 12

2-(2-anilino vinyl)-3-phenylpenthiazolinium perchlorate

Formula III

(V=H; W=CH₂; X=H; Y=C₆H₅; Z=ClO₄)

Two and nine-tenths (2.9) grams of 2-methyl-3-phenylpenthiazolinium perchlorate and 2.4 grams of diphenyl formamidine were melted at 130° C. for 10 minutes. Upon addition of isopropanol the compound crystallized. It was recrystallized from a methanol-isopropanol mixture and formed orange crystals, melting at 175° C. (Yield 2.4 grams.)

The corresponding acetyl compound

(V=CH₃-CO)

which can be obtained e. g., by acetylation of the foregoing compound with acetic anhydride, forms colorless needles, melting at 182-183° C.

EXAMPLE 13

In a similar manner other β -arylamino vinyl quaternary salts and their acyl derivatives can be prepared. Some of these are shown in the following table:

[Formula III: Y=C₆H₅; W=-]

V	X	Z	Appearance	M. P., degrees
H	H	I	Yellow needles.....	214-215
CH ₃ CO-	CH ₃	ClO ₄	Nearly colorless crystals.	188-190
H	H	ClO ₄	Yellow crystals.....	184
			Orange needles.....	191-192

1 One preparation of 2-anilidovinyl-3-phenylthiazolinium perchlorate yielded light yellow prisms (from ethanol), melting at 172-173° C. The melt, scratched with the higher melting modification of previous preparations, solidified again and melted then at 191-192° C.

These β -arylamino vinyl quaternary salts and their acyl derivatives can be converted into merocyanines by condensation with heterocyclic compounds

where D stands for oxygen or sulfur and where U stands for the non-metallic atoms necessary to complete a heterocyclic nucleus, or with other compounds having a reactive methylene group. The condensations are effected in the presence of an acid-binding agent, such as pyridine, trialkylamine, piperidine, dimethylaniline, etc. The acylarylamino vinyl cyclammonium salts, such as 2- ω -propionanilidovinyl-3-phenylpenthiazolinium perchlorate, condense with particular ease, and the condensation therefore can be carried out even at room temperature. The arylaminovinyl-cyclammonium salts, such as 2- ω -anilidovinyl-3-phenylpenthiazolinium perchlorate, however, are best condensed with the heterocyclic compounds at elevated temperature. The following example will serve to illustrate further the manner of obtaining such merocyanine dyes.

EXAMPLE 14

3-n-hexyl-5-[3-phenyl-2-(3-thiazolinylidene)ethylidene] rhodanine

Formula IV

(Q=N-n-hexylrhodanide; T=H; W=-; X=H; Y=C₆H₅; n=1)

Two and two-tenths (2.2) grams of N-n-hexylrhodanine (0.01 mol) and 4.2 grams of 2-(2-anilidovinyl)-3-phenylthiazolinium iodide (0.01 mol) were refluxed in 10 ml. of ethylalcohol with 1.4 ml. of triethylamine for two hours. By cooling, the dye crystallized; it was recrystallized from methanol and formed orange-red needles, melting at 87-88° C. Yield 3.8 grams. The solution of the dye in methanol had an absorption maximum at about 488 mu.

The dye sensitized a photographic silver bromide emulsion to about 590 mu with maximum sensitivity at about 545 mu. It is preferably used in a concentration of from about 5 to about 50 mg. per liter emulsion.

The N-n-hexylrhodanine, used in the preparation of this dye, was prepared from n-hexylamine, carbon disulfide and chloracetic acid in the usual manner, and was a viscous oil, boiling at 145° C./2 mm.

EXAMPLE 15

Other merocyanines, most of them obtained from anilidovinyl cyclammonium salts, are reported in the following table:

TABLE OF MEROCYANINES

Formula IV			T	W	X	Y	Appearance	M. P.	Absorpt., maximum mu; M = in methanol, A = in acetone	
#	n	Q								
1	1	N-phenylrhodan-	H	-----	CH ₃	C ₆ H ₅	Orange crystals (from acetone).	229°-----	A: 485.	
2	1	ylidene.	H	-----	CH ₃	p.CH ₃ C ₆ H ₄	Fire-red crystals (from acetone and methanol).	157-158°-----	A: 485.	
3	1	N-phenylrhodan-	H	-CH ₂ -	H	C ₆ H ₅	Orange crystals (from acetone).	230°-----	A: 495.	
4	1	ylidene.	H	-CH ₂ -	H	C ₆ H ₅	Fire-red crystals (from acetone and methanol).	153-155°-----	A: 492.	
5	1	Phenylmethylipyrazolonylidene.	H	-CH ₂ -	H	C ₆ H ₅	Yellow needles (from methanol).	177°-----	A: <420.	
6	2	N-n-hexylrhodan-	H	-----	H	C ₆ H ₅	Metallic soft blue crystals (from benzene and ligoine).	90-145°, depending on rate of heating.	M: 610.	
7	1	ylidene.	do	CH ₃	-----	H	n-C ₄ H ₉	Red crystals (from ethanol).	123-124°-----	M: 488.
8	1	do	do	CH ₃	-----	H	C ₆ H ₅	Red crystals (from pyridine and methanol).	142°-----	M: 488.
9	1	do	do	CH ₃ S	-----	H	C ₆ H ₅	Red crystals (from acetone).	132-133°-----	A: 515.
10	1	3-n-hexyl-2-thio-2,4-oxazolonylidene.	H	-----	H	C ₆ H ₅	Yellow crystals (from methanol).	82-83°-----	M: 455.	
11	1	3-ethyl-2-thio-2,4-oxazolonylidene.	H	-----	H	C ₆ H ₅	Rust brown crystals (from acetone and methanol).	186-187°-----	A: 444.	
12	1	N-ethylrhodan-	H	-----	H	C ₆ H ₅	Orange plates with metallic luster (from acetone).	179°-----	M: 485.	

The merocyanines 1 to 4 and 7 to 12 are strong green sensitizers for silver bromide emulsions and particularly suitable for colorphotographic emulsions containing tinctorial dyes or dye components. The sensitizing maxima of the meso substituted dyes (7 to 9) are at a little longer wavelength than those of analogous dyes having an unsubstituted polymethin chain (1 to 6; 10 to 12); the sensitizing maxima of the penthiazolino dyes (3 to 5) are at a little longer wavelength than those of analogous thiazolino dyes (1, 2, 6 to 12); and the sensitizing maxima of the dyes derived from N-arylcyclammonium salts (1 to 6, 8 to 12) are at a little longer wavelength than those of analogous dyes derived from N-alkylcyclammonium salts (7).

Substitution in the cyclamine residue (#1 and #2 of the foregoing table causes only minor shifts of the sensitizing maximum but influences the affinity of the dye to silverhalide grains, i. e., it influences the sensitizing intensity and—in color photographic multi-layer materials—the resistance to diffusion into adjacent layers and the resistance to desensitizing effects by tinctorial dyes or dye components.

By lengthening the polymethine chain (6) excellent red sensitizers are obtained. These dyes are prepared, e. g., by condensing the quaternary salts of this invention with propenedianilide (1:1) and by further condensing the intermediates hereby obtained with heterocyclic compounds such as rhodanine. The sensitizing characteristics are further influenced by the radical (Q) which can be unsubstituted rhodanine, a substituted rhodanine such as N-(β -hydroxyethyl) rhodanine, N-(β -carboxyethyl) rhodanine, N-(β -sulfoethyl) rhodanine or which can be another heterocyclic compound such as a thiooxazoledione (e. g., 3-methyl-2-thiooxazoledione), thiohydantoin (e. g., 3-ethyl-1-phenyl-2-thiohydantoin), thiobarbituric acid, pyrazolone, thiopyrazolone, thionaphthone, or which can be an acyclic compound such as malonic nitrile, etc. For example, the N-hexylthiooxazoledione merocyanine (#10 of the foregoing table) sensitizes at a shorter wavelength

than does the corresponding N-hexylrhodanine merocyanine of Example 14. It is therefore possible to prepare merocyanines from the quaternary salts of this invention which are blue, green, red or infra-red sensitizers; and by convenient variation of the above mentioned variables, sensitizers can be produced for nearly each wavelength of the spectrum.

The merocyanines of the preceding examples, 14 and 15, can be modified by addition of alkyl halides (RX), and the salts thereby obtained can be condensed with quaternary salts to give valuable trinuclear carbocyanine dyes.

Other dyes, such as styryls, pseudocyanines, isocyanines, hemicyanines, can be obtained from the quaternary salts of our invention by methods well known in the art.

The dyes of this invention may serve for sensitizing photographic silver halide emulsion, e. g., according to the following procedure: A quantity of the dye is dissolved in a suitable solvent, such as an acetone-dioxane mixture or aqueous methanol, and a volume of this solution containing from about 5 to about 100 mg. of dye is slowly added to one liter of gelatino-silver-halide emulsion. If the dye is used in sensitizing a photographic silver bromide emulsion containing a color former or a tinctorial dye, the sensitizing dye may be added to the emulsion before or after the addition of the color former or tinctorial dye, and before, during or after the ripening of the emulsion.

The dyes of our invention can be used in supersensitizing mixtures of dyes. They can be used furthermore as antihalation, filter and desensitizing dyes.

The quaternary salts of our invention, serving as intermediates for photographic dyes, may be used in other fields as well; e. g., they are valuable intermediates in the production of N-substituted aminoalkylthiols and compounds obtained therefrom.

Since from the foregoing description of the invention it will be apparent to those skilled in the art that many variations of this invention may be made without departing from the spirit and

scope thereof, it is to be understood that we do not limit ourselves to the specific examples thereof except as defined in the appended claims.

We claim:

1. A merocyanine dye represented by the 5 formula

wherein n is 1, and U represents the non-metallic atoms necessary to complete a heterocyclic nucleus selected from the group consisting of rhodanine and pyrazolone nuclei.

2. A merocyanine dye as defined in claim 1 wherein n is 1 and U represents the non-metallic atoms necessary to complete a rhodanine nucleus.

3. A merocyanine dye as defined in claim 1 wherein n is 1 and U represents the non-metallic atoms necessary to complete a pyrazolone nucleus.
